Attorney.

UNITED STATES PATENT OFFICE.

WILSON BROOKS, OF CHICAGO, ILLINOIS, ASSIGNOR TO GREAT COUNCIL OF THE UNITED STATES OF THE IMPROVED ORDER OF RED MEN, A CORPORATION.

DESIGN FOR A BADGE.

No. 39,315.

Specification for Design.

Patented May 26, 1908.

Application filed February 17, 1908. Serial No. 416,433. Term of patent 14 years.

To all whom it may concern:

Be it known that I, WILSON BROOKS, a citizen of the United States, residing at Chicago, in the county of Cook and State of Illinois, have invented a new, original, and ornamental Design for a Badge, of which the following is a specification, reference being had to the accompanying drawing, forming a part thereof.

The figure is a plan view of a badge, showing my new design.

I claim:

The ornamental design for a badge, as shown.

WILSON BROOKS.
